UNITED STATES PATENT OFFICE.

WILLIAM F. TRAUDT, OF BUFFALO, NEW YORK, ASSIGNOR TO TABER PUMP COMPANY, A CORPORATION OF NEW YORK.

ROTARY PUMP AND SIMILAR APPARATUS.

1,366,138.

Specification of Letters Patent. Patented Jan. 18, 1921.

Application filed April 22, 1919. Serial No. 291,929.

To all whom it may concern:

Be it known that I, WILLIAM F. TRAUDT, a citizen of the United States of America, residing at Buffalo, county of Erie, State of New York, have invented certain new and useful Improvements in Rotary Pumps and Similar Apparatus, of which the following is a specification.

My invention relates generally to that class of mechanism used for rotary pumps or rotary engines, and more specifically it finds its most successful application to that form of engine or pump which has a cylindrical rotor mounted eccentrically in a cylindrical casing so as to touch the casing along a common element of the two cylindrical surfaces between the inlet and outlet ports of the casing, and which rotor has two or more radial pockets each of which has a bucket mounted and movable therein so as to keep always in contact with the casing wall.

I have illustrated my invention as applied to a pump but it is obvious that if fluid under pressure were supplied to the port which is the outlet of the pump and allowed to escape from the port which serves as the inlet to the pump, the apparatus would then function as a rotary engine or motor.

Heretofore when apparatus of this kind has been used for either purpose, the main difficulty has been the "slip" or loss of fluid which passed by the buckets. In pumps of this type and ordinary construction this "slip," or shortage in the pump delivery will run over 75 per cent. of the theoretical duty if the head against which the pump is operating becomes considerable. This and various other and minor disadvantages met with in the use of this type of mechanism are overcome by my invention almost completely.

The best form of apparatus embodying my invention at present known to me is illustrated in the accompanying two sheets of drawings in which—

Figure 1 is a vertical section of a pump taken on line 1—1 of Fig. 2.

Fig. 2 is an axial, vertical section of the pump.

Fig. 3 is a similar view showing a modified form of bucket.

Fig. 4 is a perspective view of such bucket on an enlarged scale, and

Fig. 5 is a similar perspective view of the 55 packing strip used therewith.

Throughout the drawings like reference characters indicate like parts. 1, is a cylindrical casing mounted on a suitable base and having an inlet 2, and an outlet 3, spaced 60 apart circumferentially and preferably at 180 degrees. 4, is the usual rotor mounted eccentrically of the casing on shaft 7, and in contact with the casing wall along a common element of the two cylinders at a point 65 24, midway between the inlet and outlet ports. 5, 5, are buckets, preferably four in number as shown, mounted and sliding in radial pockets 26, 26, in the rotor which are spaced apart at equal distances circumfer- 70 entially thereof. 6, 6, are diagonal strips extending across ports 3 and 2, and serving to prevent the buckets flying outward and to equalize the wear over the entire outer edges of the buckets. 8, 8, are housings formed 75 on the casing 1, and in which shaft 7, is journaled. The rotor is pinned to shaft 7, by pin 9.

Each pair of oppositely disposed buckets is forced outwardly and against the casing 80 walls by springs 11, 11, compressed between them. These springs are cased in tubes 12, 12, which pass diametrically through rotor and shaft, fitting tightly in the former but movable therein. 22, 22, are sockets in the 85 inner edges of the buckets for receiving the ends of tubes 12, 12. 10, 10, are passages in the buckets leading from their inner edges, located in the rotor pockets, to points in their pressure faces (i. e. the faces exposed to pressure of the liquid passing a 90 through the apparatus, whether used as a pump or as an engine) which are exposed during the period while the bucket is passing from the inlet to the outlet port. In 95 Fig. 1, the rotor revolves clockwise, as indicated by the arrow, when the apparatus is used as a pump. It would revolve counter-clockwise if the apparatus were used as a motor.

In the modification shown in Fig. 3, the tubes 12, are provided with cross partitions 13, located approximately midway of the length of each tube. In this construction there is a shorter spring 16, on each side of 100 said partition instead of one long spring 11, going all the way through the tube as in the construction shown in Fig. 2. The tubes

also pass through little stuffing boxes 14, 14, mounted in the rotor. This construction reduces to a minimum any leakage of fluid through or around the tubes.

5 In this modification one end of each bucket is provided with a packing strip 15, having a longitudinally extending tongue 17, adapted to engage a groove 18, running along the end of the bucket. Packing strip 10 and bucket are forced apart by springs 21, 21, mounted in sockets in each, and these parts may be guided by pins 25, 25. The bucket has a cross slot 19, deeper than slot 15 or groove 18, and the packing strip has a cross tongue 20, longer than tongue 17, and registering with cross slot 19.

In operation, the fluid being pumped or used to drive the apparatus as a motor, gets between the outer edge of each bucket and 20 the casing wall while under pressure, *i. e.* during its transportation by the pump rotor and bucket from inlet port to outlet port. Whenever this pressure is considerable and not counterbalanced it will overpower 25 springs 11, or 16, and the fluid will escape to the other side of the bucket. The buckets then jump in and out with a loud chattering sound and much slip or leakage occurs. If the springs are made strong enough to prevent 30 this the wear and tear and loss of power through internal friction become prohibitive. Efforts have been made to overcome this difficulty by admitting the fluid under pressure to the bottom of the bucket 35 pockets, but in prior apparatus where this has been done the mistake has been made of dispensing with the springs and relying on the pressure alone, or on centrifugal force, to hold the buckets out and up to the work. 40 But as the pressure on the two edges of the bucket are of course approximately equal, there is not sufficient preponderance of the outward thrust of the fluid, if any, to hold the bucket against the casing, and centrifugal 45 force varies with the speed of revolution, so that until the pump reaches a certain speed of revolution the friction of the bucket in its pocket and its inertia are not overcome. Consequently the bucket does 50 not move out to contact with the casing wall and the slip, or leakage, is large until the pump reaches a high speed of revolution.

In my invention the pressures on the inner and outer edges of each bucket are 55 equalized by the flow of liquid through the bucket passages 10, 10, or through the rotor passages 23, either or both, and so the springs 11, or 16, which are given just the right force to secure a tight joint between 60 bucket and casing, are left free to exert their entire thrust for this purpose. As a result the most perfect conditions obtainable and originally created by proper design are maintained at all times.

65 The advantage of having the bucket

springs go through the rotor is that then the small relative movement between the two buckets of each pair is all that the flexing of the springs has to take care of, the springs and their incasing tubes and the 70 buckets moving back and forth nearly through the same distances and together, diametrically of the rotor. The disadvantage of the ordinary arrangement of this type is leakage or slip of fluid through and 75 around the tubes, from the pressure side of the pump to the suction side. This is eliminated in my invention by the cross partitions 18, in the tubes, and stuffing boxes 14, making tight joints with the rotor around 80 the tubes.

The spring controlled packing strip 15, is designed, of course, to take up end wear of the casing and buckets and so to prevent leakage and slip at the ends of the buckets, 85 but when the tongue 17, is partly withdrawn from groove 18, as the strip moves out after wearing down, there are passages formed between strip and bucket leading from the rotor pocket out to the suction side of the 90 bucket beyond the rotor, through which passages leakage will occur. The cross tongue 20, employed in my invention, reaches across these passages into cross slot 19, and blocks off this leakage. 95

With these refinements a rotary pump can be used to handle gasoline and other fluids of low viscosity with the highest degree of efficiency.

The diagonal bars or strips across the 100 pump ports equalize the wear on the entire outer edge of each bucket. Without these a portion of each bucket edge opposite the port is relieved from wear while passing such port, and the excess wear then resulting 105 near the extremities of the bucket edge or lip soon produces depressions there which create leakage spaces while the bucket is traveling between ports.

The simple form of pump shown in Figs. 110 1 and 2, has been run with water against a head of 80 pounds with only 16 per cent. slip, while the same pump with the pressure equalizing passages 10, plugged up gave 80 per cent. slip when working against the 115 same head.

Having described my invention, I claim:

1. In a rotary pump or similar structure the combination of a cylindrical casing provided with inlet and outlet ports spaced some 120 distance apart circumferentially, a rotor journaled in said casing and provided with radial pockets, buckets mounted and adapted to slide in said pockets, comparatively weak springs holding said buckets outward 125 against the cylindrical casing walls and means for equalizing the fluid pressure on the outer and inner edges of said buckets throughout the period of their travel from the inlet port to the outlet port. 130

2. In a rotary pump or similar structure the combination of a cylindrical casing provided with inlet and outlet ports spaced some distance apart circumferentially, a rotor 5 journaled in said casing and provided with radial pockets, buckets mounted and adapted to slide in said pockets provided with passages extending from their inner edges to points in their pressure faces exposed while 10 traveling from inlet port to outlet port, and comparatively weak springs holding said buckets outward against the cylindrical casing walls.
3. A combination such as set forth in 15 claim 1 in which the means for equalizing pressures comprises passageways extending through the buckets from the inner edges thereof to points on the pressure faces thereof exposed during the period of travel from 20 inlet to outlet port, and passages through the rotor.
4. In a rotary pump or similar structure 25 the combination of a cylindrical casing provided with inlet and outlet ports in its cylindrical walls spaced some distance apart circumferentially, a rotor journaled in said casing and provided with radial pockets, buckets mounted and adapted to slide in 30 said pockets, comparatively weak springs holding said buckets outward against the cylindrical casing walls and means for admitting to the bottom of each pocket, during the entire period of its travel from inlet to outlet port, some of the fluid which 35 is passing from one port to the other and pressing against a face of the bucket in that pocket.
5. In a rotary pump or similar structure
- having a cylindrical casing, a rotor in said casing and sliding buckets mounted in the 40 rotor, the combination, with such buckets having longitudinally grooved ends, of packing strips having tongues fitting into said grooves, and springs for forcing said packing strips outwardly, said bucket ends having cross grooves deeper than the longitudinal grooves and said packing strips having cross tongues registering with the cross grooves and longer than the longitudinal tongues.
6. A sliding bucket for use in rotary pumps and like structures having a main body grooved longitudinally along one end and cross grooved to a greater depth, a packing strip having a longitudinal tongue 55 fitting in the longitudinal groove in the bucket and a longer cross tongue fitting in the cross groove, and springs tending to force said packing strip away from the bucket body.
7. In a rotary pump or similar structure the combination of a cylindrical casing provided with inlet and outlet ports spaced some distance apart circumferentially, a rotor 60 journaled in said casing and provided with radial pockets, buckets mounted and adapted to slide in said pockets provided with passages extending from their inner edges to points in their pressure faces exposed while traveling from inlet port to outlet 65 port, and springs forcing said buckets outward against the cylindrical casing walls.
